COMPRESSED AIR SUPPLY CART OR SIMILAR ARTICLE

Joseph A. Winger, Greenwich, Conn., assignor to Texaco
Inc., New York, N.Y., a corporation of Delaware

Filed Mar. 27, 1964, Ser. No. 79,218

Term of patent 14 years

(Cl. D52—2)

FIGURE 1 is a front view of a compressed air supply cart showing my new design;

FIGURE 2 is a side elevational view thereof;

FIGURE 3 is a rear elevational view thereof; and

FIGURE 4 is a top plan view thereof.

The undisclosed side of the compressed air supply cart is substantially the same in appearance as the side shown.

The characteristic features of my design reside in the hose support trays adjacent the meter housing as shown.

I claim:

The ornamental design for a compressed air supply cart or similar article, as shown and described.
